UNITED STATES PATENT OFFICE.

JOHN FREDRICK PETERS, OF ROCHESTER, NEW YORK, ASSIGNOR TO AMERICAN CAN COMPANY, OF NEW YORK, N. Y., A CORPORATION OF NEW JERSEY.

MECHANISM FOR CURLING THE FLANGES OF CAN ENDS AND THE LIKE.

Application filed May 12, 1921. Serial No. 469,073.

To all whom it may concern:

Be it known that I, JOHN FREDRICK PETERS, a citizen of the United States, residing in Rochester, in the county of Monroe and State of New York, have invented a new and useful Improvement in Mechanism for Curling the Flanges of Can Ends and the like, of which the following is a specification.

10 My invention relates in general to metal forming machinery and has more particular reference to mechanism for curling the flanges of can ends and the like.

15 A principal object of the invention is the provision of a curling machine adapted to permit a longer course of travel of the can ends within the curling grooves without enlarging the essential units or general size of the machine.

20 A further object of the invention is the provision of mechanism of this character adapted to effect a rapid operation upon the can ends and having efficient means for transferring the ends from one stage of 25 operation to another.

Another object of the invention is the provision of a generally improved curling machine having the foregoing characteristics and adapted to be used in conjunction with 30 a press by which the ends are roughly formed, the machines being so positioned with relation to each other that the ends may be delivered through a gravity chute from the press to the curling machine.

35 Numerous other objects and advantages of the invention will be apparent as it is better understood from the following description, which, taken in connection with the accompanying drawings, discloses a preferred embodiment thereof.

Referring to the drawings:

Figure 1 is a side elevation of a curling machine, embodying my invention, and a press shown in outline in its relative position with respect to the curling machine.

45 Fig. 2 is a plan view of the curling mechanism and directing chutes.

Fig. 3 is a vertical section taken substantially on the line 3—3 of Fig. 2.

50 Fig. 4 is a fragmentary section taken substantially on the line 4—4 of Fig. 2, and showing a can end in the upper curling grooves.

Fig. 5 is a similar section taken substan-

tially on the line 5—5 in Fig. 2 and showing the end in the lower grooves.

Fig. 6 is an enlarged vertical section taken substantially on line 6—6 in Fig. 3.

Upon the drawings, which I have used for the purpose of illustrating the invention, the reference numeral 11 indicates generally a press adapted to perform a forming operation upon can ends and having a discharge chute 12 inclined downwardly. Near the base of the press is positioned a curling machine constructed in accordance with my invention and supported upon brackets 13 which in turn are secured to feet 14 bolted or otherwise attached to the floor. The curling machine comprises primarily a frame 15 which is of circular formation and has secured to an upstanding flange 16 thereon a curling ring segment 17. These parts are secured together by means of a plurality of bolts 18 which are threaded and carry nuts 19 on the exterior of the flange 16, this arrangement being for the purpose of permitting adjustment of the position of the ring segment 17. Beneath the frame 15, and having bearings in the supporting bracket 13, is a shaft 21 carrying a bevel gear 22. This gear meshes with another bevel gear 23 which is secured to a stub shaft 24 extending vertically through an aperture 25 in the central portion of the frame member 15. Secured to this shaft by means of a set screw 26 is a curling wheel 27 having a hub part 28 through which said set screw extends. Immediately beneath this hub part and extending upwardly from the bottom frame 15 about the aperture 25 is a 70 stud or projection 29 adapted to slightly elevate the wheel 27 within the frame 15.

75 Another object of the invention is the provision of a generally improved curling machine having the foregoing characteristics and adapted to be used in conjunction with a press by which the ends are roughly formed, the machines being so positioned with relation to each other that the ends may be delivered through a gravity chute from the press to the curling machine.

80 Numerous other objects and advantages of the invention will be apparent as it is better understood from the following description, which, taken in connection with the accompanying drawings, discloses a preferred embodiment thereof.

85 The curling machine comprises primarily a frame 15 which is of circular formation and has secured to an upstanding flange 16 thereon a curling ring segment 17. These parts are secured together by means of a plurality of bolts 18 which are threaded and carry nuts 19 on the exterior of the flange 16, this arrangement being for the purpose of permitting adjustment of the position of the ring segment 17. Beneath the frame 15, and having bearings in the supporting bracket 13, is a shaft 21 carrying a bevel gear 22. This gear meshes with another bevel gear 23 which is secured to a stub shaft 24 extending vertically through an aperture 25 in the central portion of the frame member 15. Secured to this shaft by means of a set screw 26 is a curling wheel 27 having a hub part 28 through which said set screw extends. Immediately beneath this hub part and extending upwardly from the bottom frame 15 about the aperture 25 is a stud or projection 29 adapted to slightly elevate the wheel 27 within the frame 15.

90 The wheel 27 is formed of two rings 31 and 32, slightly separated by blocks 33, and secured together by means of bolts 34. In these rings and extending entirely around their periphery are grooves 35 and 36, one being positioned directly above the other. It will be understood that this wheel is rotatable by means of the gearing and shafting previously described.

95 The segmental ring 17 is formed in sections 37, 38, 39, 41 and 42, these sections being secured together by means of bolts 43. In the section 39 are cut out portions 44 and 45, which, with the cooperation of the sections 38 and 41, form grooves 46 and 47.

adapted to register and cooperate with the grooves 35 and 36 in the curling wheel 27. It will be noted that this segment is of semi-circular formation extending about the front 5 part of the frame 15.

The ends 50 are received through the chute 12 in partially formed condition and guided by means of directing guides 48 and 49 between the upper grooves 35 and 46 in 10 the curling wheel and ring segment respectively, and by means of the rotation of the wheel are passed around through said grooves to the opposite extremity 51 of the segment 17. Upon reaching this point the 15 centrifugal force of the wheel 27 throws the end out of the groove 35 and into a chute 52, which is semi-circular in form and occupies generally the portion of the frame 15 opposite that in which the ring segment 17 20 is positioned. This chute is inclined downwardly in the frame, and is thus adapted to direct the ends into the lower pair of grooves 36 and 47, through which they are again passed the length of the segment 17 and 25 again thrown out by centrifugal force at the end of said segment into a passageway or chute 53, which is positioned beneath the chute 52 and leads to a discharge chute 54 in which the curled ends are stacked, it 30 being understood that the chutes 52 and 53 are positioned at the respective levels of the upper and lower pairs of grooves.

It will be manifest that the mechanism which I have provided provides increased 35 length of travel of the ends in the curling grooves and thus permits more perfect formation of the curled flanges than is possible in the ordinary curling machine, and at the same time requires no enlargement of the 40 operating units employed.

It is thought that the invention and many 45 of its attendant advantages will be understood from the foregoing description, and it will be apparent that various changes may be made in the form, construction and arrangement of the parts without departing from the spirit and scope of the invention or sacrificing all of its material advantages, the form hereinbefore described being 50 merely a preferred embodiment thereof.

I claim:

1. Mechanism for curling the flanges of can ends and the like, comprising inner and outer curling units having a common center, 55 each of said units having a plurality of sets of cooperating curling grooves, said sets being arranged on different levels, and means for passing the ends through each of said sets of grooves.

60 2. Mechanism for curling the flanges of can ends and the like, comprising inner and outer curling units having a common center, each of said units having a plurality of sets 65 of cooperating curling grooves, said sets being operatively consecutive one after the

other, and being arranged on different levels whereby to increase the length of travel of the ends in the curling mechanism without increasing the size of said mechanism, and means for passing the ends through each 70 of said sets of grooves.

3. Mechanism for curling the flanges of can ends and the like, comprising inner and outer curling units having a common center, 75 each of said units having a plurality of sets of cooperating curling grooves, one of said units being rotatable and the sets of grooves being arranged on different levels, and means for passing the ends through each of said sets of grooves. 80

4. Mechanism for curling the flanges of can ends and the like, having in combination a plurality of curling units, each of said units having a plurality of separate superposed sets of curling means, and means for passing the can ends through each of said sets. 85

5. Mechanism for curling the flanges of can ends and the like, comprising inner and outer curling units having a common center, 90 each of said units having a plurality of sets of cooperating curling grooves, said sets being arranged on different levels, and means for passing the ends through each of said sets of grooves, said means comprising a device for rotating one of said curling units and an inclined chute for transferring the ends from one set of grooves to another. 95

6. Mechanism for curling the flanges of can ends and the like, comprising inner and outer curling units having a plurality of sets of cooperating curling grooves, said sets being arranged on different levels, and means for passing the ends through each 100 of said sets of grooves, one of said curling units being a rotatable wheel having grooves extending entirely about its periphery and the other being stationary and of semi-circular formation. 105

7. Mechanism for curling the flanges of can ends and the like, comprising a frame 110 of circular formation, a rotatable curling wheel mounted therein, a curling ring segment positioned outwardly from said wheel and within said frame, there being sets of grooves in said wheel and ring segment arranged upon different levels, and means for passing the ends through each set of grooves. 115

8. Mechanism for curling the flanges of can ends and the like, comprising a frame of circular formation, a rotatable curling wheel mounted therein, a curling ring segment positioned outwardly from said wheel and within said frame, there being sets of 120 grooves in said wheel and ring segment arranged upon different levels, and means for transferring the ends from one set of grooves to another. 125

9. Mechanism for curling the flanges of can ends and the like, comprising a frame 130

of circular formation, a rotatable curling wheel mounted therein, a curling ring segment positioned outwardly from said wheel and within said frame, there being sets of 5 grooves in said wheel and ring segment arranged upon different levels, and means for revolving said curling wheel and for passing the ends through the several sets of grooves and out of the machine.

10 10. Mechanism for curling the flanges of can ends and the like, comprising a frame of circular formation, a rotatable curling wheel mounted therein, a curling ring segment positioned outwardly from said wheel and within said frame, there being sets of 15 grooves in said wheel and ring segment arranged upon different levels, means for revolving said curling wheel and for passing

the ends through the several sets of grooves and an inclined discharge chute adapted to 20 receive the curled ends.

11. Mechanism for curling the flanges of can ends and the like, comprising a frame of circular formation, a rotatable curling wheel mounted therein, a curling ring segment positioned outwardly from said wheel and within said frame, there being sets of 25 grooves in said wheel and ring segment arranged upon different levels, means for directing the ends into cooperating grooves 30 in said wheel and ring segment and an inclined directing passage or chute for transferring said ends from one set of grooves to another.

JOHN FREDRICK PETERS.
